UNITED STATES PATENT OFFICE.

CHARLES P. COSCIA, OF PITTSBURGH, PENNSYLVANIA.

SHOE.

1,351,414.

Specification of Letters Patent. Patented Aug. 31, 1920.

Application filed December 20, 1919. Serial No. 346,365.

To all whom it may concern:

Be it known that I, CHARLES P. COSCIA, a citizen of the United States, residing at Pittsburgh, in the county of Allegheny and State of Pennsylvania, have invented certain new and useful Improvements in Shoes, of which the following is a specification.

This invention relates to a new and useful article of manufacture comprising a unitary front half of a shoe adapted to be used in connection with the repairment of shoes.

In the majority of instances the front or vamp portion of a worn shoe is the first to show the effects of wear while the heel or back portion of the shoe is still generally in a fair or good condition, and if a new front half of a shoe is devised that can be employed with an old heel or back portion a substantially new shoe is produced.

It is the object of this invention to provide, as an article of manufacture, a unitary article comprising a vamp, welt and inner and outer soles, all of which are secured together, and so set up that when the front half of a worn shoe is detached from the back or heel half of the shoe, the unitary article, termed front half of shoe, can be conveniently attached or secured to the back half, thereby resulting in the production of a substantial and good shoe, and the advantageous economy concomitant therewith.

Other objects of this invention are to provide an article of manufacture for the purpose specified, in a manner as hereinafter set forth, which is simple in its construction and arrangement, strong, durable and efficient in its use, and comparatively inexpensive to manufacture and attach.

To the accomplishment of these and such other objects as may hereinafter appear the invention consists of the novel construction, combination and arrangement of parts herein specifically described and illustrated in the accompanying drawing wherein is shown embodiments of the invention, but it is to be understood that the device shown is merely illustrative and that various changes in the form, proportion and minor details of construction may be resorted to, without departing from the principle or sacrificing any of the advantages of the invention, which come within the scope of the claims hereunto appended.

In the drawing forming a portion of this specification and wherein like numerals of

reference designate corresponding parts throughout the several views:

Figure 1 is a perspective view of a unitary front half of a shoe in accordance with this invention and further showing in dotted lines the back half of a shoe in position relative to the front half.

Fig. 2 is a perspective view of a modified form of a unitary front half of a shoe in accordance with this invention.

Referring to Fig. 1 of the drawings 1 denotes a vamp, 2 an inner sole, 3 a welt and 4 an outer sole. The welt, vamp, inner, and outer soles are secured together in a known manner. The welt and outer sole project rearwardly from the vamp and the free ends thereof are skived off whereby they can be conveniently fitted and secured to the back or heel half of the shoe, said back half being shown in dotted lines and indicated at 5. The in-sole 2 projects beyond the welt but does not overlap or extend to the free or rear end of the outer sole 4. The rear end of the outer sole 4 is rounded and when the front half is secured to the back half the rear end of the outer sole does not extend entirely across the top of the heel.

The vamp is disconnected from the welt at the beginning of the arch portion of the outer sole and the welt is disconnected from the outer sole at the beginning of the said arch portion. The vamp is secured to the in-sole 2, but the latter projects therefrom and is disconnected from the projecting rear portions of the welt and outer sole. The disconnected rear portions of the in-sole 2, welt 3 and vamp 1 facilitate the securing of the front half of the shoe to the back half and such disconnected portions enable the positioning of the outer sole with respect to the heel and the position of the upper of the back portion with respect to the outer sole, in-sole and welt.

The structure described provides a unitary front half of a shoe which can be sold as such and which can be readily employed for repair work in foot gear and which can be quickly attached to the back or rear half of a shoe.

In the modified form shown in Fig. 2, the vamp is indicated at 6, the welt at 7, the in-sole at 8 and the outer sole at 9. The in-sole, welt and outer sole project rearwardly from the vamp and the portions which project from the vamp are disconnected from

each other, that is to say the in-sole is disconnected from the welt and the latter from the outer sole; under such conditions the back or heel half of a shoe can be conveniently connected with the vamp, insole, welt and outer sole. The in-sole or the outer sole is not cut away and the same is true of the welt, and are of such length as to be flush with the periphery of the heel of the back half of the shoe when the front half is secured to said back half. The structure just set forth provides a unitary front half of a shoe so set up that it is sold as such and which can be quickly and conveniently attached to the back half of a shoe.

What I claim is:

1. As a new article of manufacture a unitary front half of a shoe comprising a vamp, a welt, an in-sole and an outer-sole, said in-sole secured to said vamp and projecting rearwardly therefrom, said vamp, welt and outer-sole secured together and said welt and outer-sole projecting rearwardly from said vamp, said rearwardly projecting portion of the in-sole disconnected from the rearwardly extending portion of the welt, and said rearwardly extending portion of the welt disconnected from the rearwardly extending portion of the outer-sole.
2. As a new article of manufacture a unitary front half of a shoe comprising a vamp, a welt and an outer-sole, said vamp, welt and outer-sole secured together, and said welt and outer-sole projecting rearwardly from said vamp, said rearward ex-

tension of said welt disconnected from the rearwardly extending portion of the outer-sole.

3. As a new article of manufacture a unitary front half of a shoe comprising a vamp, a welt, an in-sole and an outer-sole, said vamp, welt, in-sole and outer-sole secured together, said welt, in-sole and outer-sole projecting rearwardly from said vamp, said rearwardly extending portions of said welt, in-sole and outer-sole disconnected from each other.

4. As a new article of manufacture a unitary front half of a shoe comprising a vamp, a welt, an in-sole and an outer-sole, said welt, in-sole and outer-sole and vamp secured together, and said insole, welt, and outer-sole projecting rearwardly from said vamp, said rearwardly extending portions of said in-sole, welt and outer-sole disconnected from each other, and said welt and outer-sole having the rear ends thereof skived off.

5. As a new article of manufacture a shoe repair element consisting of a unitary body formed from a covering extending transversely of, overlapping and secured to the lower face of a portion of an inner sole, said inner sole projecting rearwardly from said covering, said body further including a welt secured to the overlapping portion of said covering and having its ends disconnected from the inner sole.

In testimony whereof I affix my signature.

CHARLES P. COSCIA.
